UNITED STATES PATENT OFFICE.

WINTHROP L. JACOBS, OF EAST ORANGE, NEW JERSEY, ASSIGNOR TO THE
HARTFORD CARPET COMPANY, OF HARTFORD, CONNECTICUT.

DESIGN FOR A CARPET.

SPECIFICATION forming part of Design No. 14,876, dated March 11, 1884.

Application filed January 23, 1884. Term of patent 7½ years.

To all whom it may concern:

Be it known that I, W. L. JACOBS, of East Orange, in the State of New Jersey, have invented a new and original Design for Carpets, 5 of which the following is a specification, reference being had to the accompanying photograph which forms a part of the same.

The invention relates to a design to be worked into or upon surfaces, such as carpets 10 or similar fabrics; and it consists in the novel configuration and grouping of figures herein specifically shown and claimed.

The accompanying photograph is a face view 15 of a carpet showing my new design.

Scattered irregularly over the face of the de-

sign are different and variously shaped full-flower forms, with straight stems connecting them with one another. In the background there are shadow-flower forms scattered in the same irregular manner over the design. 20 The general effect of the design is produced by the interblending of the full and the shadow flower forms and the interlacing stems.

I claim—

The design for a carpet, substantially as 25 shown and described.

W. L. JACOBS.
